US00D886203S

(12) **United States Design Patent** (10) **Patent No.:** **US D886,203 S**
Hsu (45) **Date of Patent:** **** Jun. 2, 2020**

(54) **CHESS SET**

(71) Applicant: **Carolyn Hsu**, San Francisco, CA (US)

(72) Inventor: **Carolyn Hsu**, San Francisco, CA (US)

(**) Term: **15 Years**

(21) Appl. No.: **29/629,664**

(22) Filed: **Dec. 14, 2017**

(51) **LOC (12) Cl.** **21-01**

(52) **U.S. Cl.**

USPC **D21/349**

(58) **Field of Classification Search**
